US00D552465S

(12) **United States Design Patent** (10) Patent No.: **US D552,465 S**
 Ringo (45) Date of Patent: ** Oct. 9, 2007

(54) **SHEATHED REUSABLE RETAIL DISPLAY AND STORAGE UNIT FOR ELECTRONICS COMPONENTS**

(75) Inventor: **Scott Andrew Ringo**, Euless, TX (US)

(73) Assignee: **Dobbs-Stanford Corporation**, Dallas, TX (US)

(**) Term: **14 Years**

(21) Appl. No.: **29/227,835**

(22) Filed: **Apr. 15, 2005**

(51) **LOC (8) Cl. 09-03**

(52) **U.S. Cl. D9/415; D3/273**

(58) **Field of Classification Search** D9/711, D9/414, 432, 456, 501, 419, 415, 503, 424, D9/430; 206/541, 395, 397, 398, 223, 769; 220/555, 556, 544; 229/87.08, 87.018, 103.2; D13/153, 139.1; D3/273

See application file for complete search history.

(74) Attorney, Agent, or Firm—Storm LLP; John G. Fischer

(57) **CLAIM**

The ornamental design for a sheathed reusable retail display and storage unit for electronics components, as shown and described.

DESCRIPTION

FIG. 1 is an isometric view thereof;

FIG. 2 is side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

1 Claim, 4 Drawing Sheets

FIG. 1

FIG. 2

FIG. 3

FIG. 4

FIG. 5

FIG. 6

FIG. 7
